COMBINATION HAND TOOL FOR BOY SCOUTS,
HUNTERS, WOODSMEN AND THE LIKE

Francis H. Monek, 950 E. Westminster, Lake Forest, Ill.

Filed July 26, 1963, Ser. No. 75,979

Term of patent 14 years

(Cl. D54—13)

FIG. 1 is a front elevational view of a combination hand tool for Boy Scouts, hunters, woodsmen and the like, embodying my new design;

FIG. 2 is a rear elevational view thereof;

FIG. 3 is an edge elevational view as seen from the left-hand side in FIG. 1;

FIG. 4 is an edge elevational view as seen from the right-hand side in FIG. 1;

FIG. 5 is a top plan view as seen from the top in FIG. 1; and

FIG. 6 is a bottom plan view as seen from the bottom in FIG. 1.

The dominant features of the design are shown in full lines in the drawing.

I claim:

The ornamental design for a combination hand tool for Boy Scouts, hunters, woodsmen and the like, substantially as shown and described.
